UNITED STATES PATENT OFFICE.

RICHARD DENNIS STACEY, OF MALDON, VICTORIA, AUSTRALIA.

SCREEN.

1,031,482.

Specification of Letters Patent. Patented July 2, 1912.

Application filed March 7, 1912. Serial No. 682,223.

To all whom it may concern:

Be it known that I, RICHARD DENNIS STACEY, a subject of the King of Great Britain and Ireland, and a resident of Laurence street, in the post town of Maldon, in the county of Talbot, State of Victoria, Commonwealth of Australia, have invented certain new and useful Improvements in Screens, of which the following is a specification.

This invention relates to screens of the character consisting of a series of laths adapted to be drawn into a restricted area and also capable, when extended, of being opened apart to admit light or ventilation.

The object of the invention is to provide a simple screen which will be fire proof and weather resisting. In addition by the screen ventilation may take place with safety and without unnecessary movement or rattling.

The screen may be used for window purposes or as a fire guard to prevent burning embers falling out of a domestic grate.

It may also be used to assist the draft in starting a fire.

It may, further, be used as an advertising screen and for a variety of other purposes, not being cumbersome or unsightly.

Referring to the drawings which form a part of this specification:—Figure 1 is an isometric view of portion of a screen to show the relationship between laths thereof. A lower lath is open acting as a ventilator. Fig. 2 is a front view of this invention, on a reduced scale, portion being broken away for convenience of illustration. Fig. 3 is an enlarged detail view of two inter-engaging hinge rolls. Fig. 4 is an end sectional view on a reduced scale, the screen being shown as partly elevated to illustrate the movement of the laths during the elevating operation. It is obvious that an elevating line and a lower lath inclining line have been delineated in unnatural positions for convenience of illustration. Pulleys and holes adjoining them have also been positioned for illustrative purposes only and need not occupy the positions shown. Fig. 5 is an end sectional view, on a reduced scale, the screen being fully extended. Lower laths are open to admit light or ventilation. It is obvious that an elevating line and a

lower lath inclining line have been delineated in unnatural positions for convenience of illustration. Pulleys and holes adjoining them have also been positioned for illustrative purposes only and need not occupy the positions shown.

The invention includes (Figs. 2, 4 and 5) a framework consisting of a top member 2 to which are attached suitable hinges 3. Below the top member 2 is a bottom member 4 and extending between the top and bottom members are side members 5. From the side members may protrude studs 6. Secured to each side member 5 is an outer guide member 7 and an inner guide member 8. The framework may consist of any suitable material or materials and vary in conformation according to the circumstances surrounding its use.

Formed in the top member and near the center of the same is an elevating line hole 9. Adjoining the hole 9 is an elevating line inner pulley 10. Near one end of the top member 2 is an elevating line outer pulley 11. Formed in the top member 2 is also a lower lath inclining line hole 12. Adjoining the hole 12 is a lower lath inclining line inner pulley 13. Near one end of the top member 2 is secured a lower lath inclining line outer pulley 14.

Within the framework is a screen consisting of a series of members. Each member includes an upper lath having two longitudinal edge portions 15 and 16 thereto. The screen is retained within the framework by means of the hinges 3 which are attached to the edge portion 15 of the extreme upper lath of the said screen. Formed in each upper lath and near the center of the same is an elevating line slot 17. Each screen member also includes a lower lath having two longitudinal edge portions 18 and 19 thereto. Formed in each lower lath near the center of the same is an elevating line slot 20. Formed in each lower lath near the edge portion 19 thereof is a lower lath inclining line hole 21.

The upper lath of each screen member is provided along its edge portion 16 with a hinge roll 22. The lower lath of each screen member is provided along its edge portion 18 with a hinge roll 23. The hinge rolls 22

and 23 interengage as shown in Fig. 3. Any other suitable hinge may be used, however, if desired.

Uniting the lower lath of each screen member with the upper lath of the member beneath it are links. Each link has an upper end 24 and a lower end 25. The upper end 24 of each link is hingeably attached to the edge portion 18 of a lower lath. The lower end 25 of each link is hingeably attached to the edge portion 15 of an upper lath as shown.

With the foregoing is used an elevating line having an inner end 26 and an outer end 27. The inner end 26 is secured to the extreme lower lath of the screen. The line is passed upwardly through the elevating line slots, over the inner pulley 10 and outer pulley 11, as shown. With the foregoing is also used a lower lath inclining line having an inner end 28 and an outer end 29. Upon the line are stops 30. The inner end 28 of the lower lath inclining line is secured to one of the lower laths of the screen and passed upwardly through the lower lath inclining line holes 21, over the pulleys 13 and 14. The inner end 28 may be attached to the extreme lower lath of the screen. Or it may be secured to the lower lath above it as shown.

With this invention, to elevate or lower the screen it is only necessary to operate the elevating line. The action of elevation is shown in Fig. 4. When the screen is extended and it is desired to open the lower laths the inclining line is pulled. This moves the lower laths from a vertical toward a horizontal position. The lowest of the lower laths may be operated by the elevating line if desired as will be clear from the drawings. When operating the lower laths by the lower lath inclining line the stops 30 it will be seen, in turn engage with their corresponding lower laths. Ventilation or light is thus admitted through the screen.

It will be plain that instead of two central lines being used to operate the screen, lines could be used at each side thereof and be connected. Any suitable guide rods or the like may also be used in conjunction with the laths.

Having now described my invention, what I claim as new and desire to secure by Letters Patent is:—

1. A screen consisting of a series of laths hinged together in pairs, an upper lath and a lower lath forming each pair, and means for laterally inclining the lower laths without interfering with the upper laths.

2. A screen consisting of a series of laths hingeably arranged in pairs, an upper lath and a lower lath forming each pair, and links hingeably holding the upper lath of

each pair to the lower lath of the pair above it.

3. A screen consisting of a series of laths hinged together in pairs, an upper lath and a lower lath forming each pair, a line for laterally inclining the lower laths, and a line for elevating and lowering the whole series of laths.

4. A screen consisting of a series of laths hinged together in pairs, links hingeably connecting successive pairs, an inclining line having stops therein engaging alternate laths, and an elevating line for moving the whole series of laths.

5. A screen consisting of a series of laths arranged in pairs, interengaging hinge rolls hinging the laths of each pair together, links hingeably connecting the pairs of laths, an elevating line for elevating and lowering the series of laths, and an inclining line having stops thereon for operating alternate laths.

6. A screen having a framework, including guide members, line pulleys carried by said framework, screen members within said framework and consisting of a series of laths hingeably arranged in pairs, links hingeably connecting successive pairs of laths, an elevating line for elevating and lowering the series of laths, and an inclining line having stops thereon for operating alternate laths.

7. A screen comprising an upper lath, a lower lath, intermediate hinge rolls carried by said laths, means for elevating the lower lath, and means for folding and elevating both the upper and lower laths.

8. In a screen, a series of pairs of laths, an upper lath and a lower lath to each pair, interengaging hinge rolls carried by each pair, and links hingeably connecting the pairs of laths.

9. In a screen, a series of pairs of laths, an upper lath and a lower lath to each pair, interengaging hinge rolls carrier by each pair, links hingeably connecting the pairs of laths, a top member hingeably supporting the series, an elevating line for lifting and lowering the series, and an inclining line for operating alternate laths.

10. In a screen, a framework having a top member, line pulleys carried by said top member a series of pairs of laths hingeably supported by said top member, an upper lath and a lower lath to each pair, interengaging hinge rolls carried by each pair, links hingeably connecting the pairs of laths, an elevating line for lifting and lowering the series, an inclining line for operating alternate laths, and stops upon the inclining line.

11. In a screen, a framework having therein a series of pair of laths, an upper lath and a lower lath to each pair, interengaging hinge rolls carried by each pair, certain of the laths having an elevating line

slot, certain of the lower laths having inclining line holes, an elevating line passing through the line slots and an inclining line passing through the line holes.

- 5 12. A screen, having a framework, line pulleys carried by said framework, a series of pairs of laths within said framework, an upper lath and a lower lath to each pair, interengaging hinge rolls carried by each 10 pair, certain of the laths having an elevating line slot, certain of the lower laths hav-

ing line holes, an elevating line passing through the line slots, an inclining line passing through the line holes, and stops upon the inclining line.

15

In testimony whereof I affix my signature in presence of two witnesses.
